(57) **CLAIM**

The ornamental design for a can shaped automated teller machine, as shown and described.

DESCRIPTION

FIG. 1 is a perspective view of a can shaped automated teller machine according to this invention;

FIG. 2 is a reduced front view of the automated teller machine shown in FIG. 1;

FIG. 3 is a reduced top view of the automated teller machine shown in FIG. 1;

FIG. 4 is a reduced rear view of the automated teller machine shown in FIG. 1; and,

FIG. 5 is a reduced bottom view of the automated teller machine shown in FIG. 1.

The broken lines illustrate the environment in which the article embodying the design is used and form no part of the claimed design or of a specified embodiment thereof.
